UNITED STATES PATENT OFFICE.

HARRIETTE GROSS COZZINO, OF NEW YORK, N. Y.

DESIGN FOR A HAT-SUPPORT.

SPECIFICATION forming part of Design No. 27,558, dated August 24, 1897.

Application filed July 7, 1897. Serial No. 643,766. Term of patent 7 years.

To all whom it may concern:

Be it known that I, HARRIETTE GROSS COZZINO, a citizen of the United States, residing at New York city, in the county and State of New York, have invented and produced a new and original Design for a Hat and Garment Support for Theater-Chairs, of which the following is a full, clear, and exact description, reference being had to the accompanying drawings, forming a part thereof, in which—

Figure 1 is a perspective view of the hat and garment support embodying the features of my design, and Fig. 2 is a vertical central 15 section through the support.

The design is especially adapted for hat and garment supports, being particularly designed for theater-chairs, and the object sought is to provide an ornamental device which in addition to serving as a rack will greatly facilitate rearranging or making one's toilet.

The leading feature of the design consists of a body A, of a shape adapting it for application to the back of a chair, a front member B, spaced from and connected with the body, 25 and a polished or reflecting surface C, appearing pivotally at the front member.

Another feature of the device consists in the divided form of the body and in the upward inclination of the connecting medium 30 between the body and the front of the device.

I claim—

The design for a hat and garment support for theater-chairs, substantially as herein shown and described.

HARRIETTE GROSS COZZINO.
